John A. Sprague

UNITED STATES PATENT OFFICE.

MICHAEL A. McCARRON, OF DETROIT, MICHIGAN, ASSIGNOR OF TWO-THIRDS
TO THEODORE P. BYRAM, OF SAME PLACE.

CAR-BRAKE.

SPECIFICATION forming part of Letters Patent No. 366,418, dated July 12, 1887.

Application filed February 3, 1887. Serial No. 226,369. (No model.)

To all whom it may concern:

Be it known that I, MICHAEL A. McCARRON, of Detroit, in the county of Wayne and State of Michigan, have invented new and useful 5 Improvements in Car-Brakes; and I do hereby declare that the following is a full, clear, and exact description thereof, reference being had to the accompanying drawings, which form a part of this specification.

10 This invention relates to certain new and useful improvements in car-brakes, the object of the invention being to construct a brake wherein the brake-shoes are simultaneously closed upon a brake pulley secured upon the 15 axle.

The invention consists in the peculiar arrangement of the brake-shoes, in combination with the operating levers and rods, all as more fully hereinafter set forth.

20 Figure 1 is a perspective view showing my improved device applied to the axles of a street-car. Fig. 2 is a vertical sectional elevation showing arrangement of brake shoes, levers, and springs. Fig. 3 is a plan.

25 In the accompanying drawings, which form a part of this specification, A A represent the axles of a car, to which are rigidly secured the brake-pulleys B.

30 C are hoods, one being placed over each pulley B, said hoods resting upon the axles in proper bearings, preferably made in two parts, that will admit of their being easily adjusted to the axles without rendering it necessary to remove the trucks or of jacking up the car-body. These hoods are connected together by a suitable bar, D, to which is pivotally secured the brake-lever E, the ends of which are connected in the usual manner to the brake-staffs.

35 F and G are brake-shoes pivotally secured near their upper ends in the hoods C. To the sides of the shoes G are pivotally secured the

links or levers H, one end of such links being connected by means of a bifurcated pull-rod, I, to the brake-lever E.

45 J are pull-rods connecting the levers H with the shoes F.

In the top of the hood C is secured a spring, K, the ends of which bear upon the upper ends of the brake-shoes, and compel the latter to 50 assume their normal positions free from contact with the pulleys B when the brake-staffs are released.

By this construction and arrangement of parts it will readily be seen that, the brake-staffs being operated in the usual manner, the 55 pull-rods I and J compel the shoes F and G to simultaneously advance toward the brake-pulleys, and, if properly hung, will simultaneously come in contact therewith. Sufficient 60 force being applied will, by frictional contact between the brake shoes and pulleys, stop the rotation of the latter, and thus stop the inertia of the car. Upon releasing the brake-staffs the springs compel the shoes to assume their 65 original positions.

What I claim as my invention is—

1. In a car-brake, the combination, with the axles A, of the pulleys B, hoods C, connecting-bar D, brake-lever E, shoes F and G, levers 70 H, and pull-rods I and J, substantially as and for the purposes set forth.

2. In a car-brake, the combination, with the axles A, of the pulleys B, hoods C, connecting-rod D, brake lever E, shoes F and G, levers 75 H, pull-rods I and J, and springs K, the parts being constructed, arranged, and operating substantially in the manner and for the purposes described.

MICHAEL A. McCARRON.
